J. C. COX ET AL.

CAR COUPLING

Filed May 19, 1923

Fig. 1.

Fig. A.

Fig. 3.

Fig. 2.

A technical line drawing of a mechanical component. It features a central vertical rod with a stepped profile, supported by a horizontal frame. The frame has several mounting points labeled with numbers: 1, 2, 3, 4, 5, 6, 7, and 8. Point 1 is at the top right, 2 is at the top left, 3 is on the left side, 4 is at the bottom left, 5 is on the right side, 6 is at the bottom right, 7 is at the bottom left, and 8 is at the bottom right. There are also some smaller, unlabeled points indicated by dashed lines.

ATTORNEY.

UNITED STATES PATENT OFFICE.

JOHN C. COX AND JOHN C. ALDRIDGE, OF CENTRALIA, ILLINOIS.

CAR COUPLING.

Application filed May 19, 1923. Serial No. 640,178.

To all whom it may concern:

Be it known that we, JOHN C. COX and JOHN C. ALDRIDGE, citizens of the United States, and residents of Centralia, in the county of Marion and State of Illinois, have invented certain new and useful Improvements in Car Couplings, of which the following is a specification.

This invention relates to car couplings and more particularly to couplings for use upon mine cars.

It is an object of this invention to provide a coupling which will be easy to manipulate, of few parts, simple in construction, yet strong and durable, and inexpensive to manufacture.

The device consists of a member having a bifurcated head, one end securely bolted to the floor of a car, the bifurcated head extending beyond the floor, the inner faces of each of the furcations being provided with aligned forwardly curved grooves, the upper ends of each of which open out upon the upper surface of the head. A T-shaped casting is provided for engagement in said grooves, the ends of the cross arm seating in the curved grooves, while the body is positioned between the furcations. The leg of the casting is provided with an aperture through which a link is passed for connection with the leg of another casting of like construction as the first which same may be connected to a similar head on another car body or a clevis or other suitable type of connection may be made use of at the other end.

A clear and better understanding may be had of the device upon reference to the accompanying sheet of drawing, in which:—

40 Figure 1 is a top plan view, partly in section, of the device shown attached to the floors of two car bodies.

Figure 2 is a side view partly in vertical longitudinal section.

45 Figure 3 is a section of the connecting head, taken on the line 3—3, of Figure 1.

Figure 4 is a detail view of the T-casting and connecting link, and,

Figure 5 is a detail of the connecting head.

50 Referring now in detail to the various views of the drawing, in which like numerals indicate like parts in each of the several views, numerals 1—1, indicate the floor of a car and 2 the draw bar of the same.

55 A member 3, is connected to the draw bar, and is provided with a transverse slot 4

into which the draw bar is positioned, sufficient space being provided between the upper surface of the floor and the bar 2, to allow the under leg of the member 3 to be positioned therebetween. A sufficient number of bolts 5, are passed through the three members 1, 2 and 3 to securely hold the same together, the forward bolt passing through a binder 6, on the under surface of the car 65 against which the nut is tightened.

The forward end of the member 3, which overhangs the car floor, terminates in an enlarged bifurcated connecting head 7, each of the furcations of which has formed in 70 its inner face forwardly curved aligned grooves 8, which open upon the upper surface of the head near the rear of the furcations as shown.

Connecting the cars by engagement with 75 the heads 3, are T-shaped castings having a flat body 9, of greater thickness at one end 9^a, than at the other. The thickened ends of the castings are provided with lateral arms 10 which are adapted to engage the 80 grooves 8, the thickened part 9^a, of the body 9, occupying the space between the furcations of the head 7. The end of 9, carrying the arms 10, is rounded, as shown, and increases in width to the opposite end which 85 is likewise rounded, this end being provided with an aperture 11, through which a connecting link 12, extends for connecting the castings.

In order that the grooves 8, be protected 90 and to prevent the arms 10, from riding up and out of the grooves should the connecting heads 7, come together, a cover plate 13 of the same contour as the head is attached thereto by a screw threaded bolt 14, 95 the head of which is raised sufficiently to allow the plate to be swung to one side when it is desired to disconnect the cars.

Having thus described the invention in accordance with the showing of the drawing, it is to be understood that various changes and modifications may be made in the structure without departing from the spirit of the invention as embodied in the claim.

What is claimed is:—

In a car coupling of the character described, a connecting member having one end formed to provide means for connection with a draw bar and having its other end enlarged and provided with a vertical slot 110 to form a bifurcated head having the in-

ner faces of the furcations parallel throughout, said inner faces of the furcations having formed therein grooves of equal width throughout, each describing an arc of approximately one quarter of a circle and extending from the upper surface of the head adjacent the rear of the furcations, downwardly and forwardly in the face thereof, and a broad, flat connecting member having laterally extending pins upon the longi-

tudinal center of each side thereof, said member fitting snugly between said parallel faces to prevent side movement of the member and said pins adapted to be so pocketed in said grooves as to be completely covered by the overlying walls thereof. ¹⁵

In testimony whereof, we affix our signatures hereto.

JOHN C. COX.
JOHN C. ALDRIDGE.
